UNITED STATES PATENT OFFICE.

BEN ROBERT SMITH, OF PENSACOLA, FLORIDA.

RAILWAY-SIGNAL-LOCKING DEVICE.

Application filed November 10, 1927. Serial No. 232,209.

This invention relates to an improved signal device embodying a safety factor and specifically to a signalling device which is particularly adapted for use by railroads.

5 It is an object of the invention to provide a device of this character by means of which, while when a signal is in clear position it may readily be actuated to indicate a caution or stop signal, when by reason of an order the 10 signal has been set in either of such latter positions, it may not be shifted to the clear position in a careless or casual manner, the return to such position requiring a proper sequence of operations.

15 A still further object of the invention is that of providing in conjunction with a signal a construction by means of which the signal will be set virtually automatically to the required caution or stop position, according 20 to the dignity of the order, and at the time such order is about to be inscribed.

Still another object is that of providing such a device in which the parts will be few in number, rugged, and relatively simple in 25 construction; to furnish a signal which may be assembled readily and will operate over long periods of time with freedom from mechanical difficulty.

An additional object is that of devising a 30 safety device for signals which may be applied to signals already in existence, without requiring a reconstruction of such signals.

Reference is had to the attached sheets of 35 drawings illustrating practical embodiments of the invention, and in which:

Figs. 1, 2 and 3 are side elevations partly in section of one form of safety signal embodying the improved construction of the present invention;

40 Fig. 4 is a perspective view of certain of the operating mechanism therefor;

Fig. 5 is a similar view of the receptacle and closure which may be employed; and

45 Figs. 6 and 7 show two different forms of signalling device as embodying my present invention.

In these views the numeral 10 indicates the 50 column or standard supporting, at its upper end, the semaphore arm 11 which may, in accordance with conventional construction, be formed with three apertures 12, each presenting a differently colored lens or window through which, from a suitable source of illumination (not shown) rays may be directed along the right of way.

Furthermore, as is conventional, these semaphore arms may extend in horizontal position when indicating a stop signal, in inclined position (approximately 45°) to register a caution signal, and extend vertically only 60 when the right of way is clear.

It is well understood by those conversant with railroad practice, that two types of orders are in common usage: one, in which its importance is not of sufficient dignity to warrant stopping a train unless through some accident in its relay to the train the crew of the latter fails to receive it; the other order is one of utmost importance, and involves not alone bringing the train to a complete stop, 70 but requires that the dispatcher or agent deliver the order to the train crew and secure from them a receipt for such order. It has heretofore occurred through carelessness on the part of the person who received the order 75 and was to transfer it to the train crew, that the semaphore has not been set to proper position and accordingly upon the approach of the train has indicated a clear right of way, resulting in accidents. 80

By means of the present invention it is proposed, with particular reference to this phase of railroading, to provide a check on the official or operator who is to transmit the orders, and which check will render it necessary, upon the writing of an order to be transmitted to an approaching train, for such operator to set the semaphore to a position commensurate with the dignity of the order. It is, furthermore, proposed by means of the 90 present invention to prevent a subsequent resetting of the semaphore to its initial position without requiring a series of acts, the latter being virtually incapable of performance by an operator without deliberate intent 95 on his part.

Thus, in Figs. 1 to 3, the semaphore arm in the first figure indicates a stop position, in Fig. 2 a caution position, and in Fig. 3 a clear position. With a view to actuating 100 such arms in these figures, a lever 13 is pivoted to the standard and has an actuating member 14 attached to one of its ends, a link 15 being secured to its opposite end and connecting with the arm 11 for the purpose of shifting the same around its point of pivotal connection with the standard. In accordance with conventional practice the inner end of the lever 13 may be weighted as at 16 and the semaphore arm may have its body disposed 105 110

so that the entire device will normally tend to maintain the stop position of the semaphore arm, it being understood that any desired retaining means (not shown) may be employed to retain the actuating member in the position to which it has been shifted.

Disposed in proximity to the standard 10, and preferably adjacent the base thereof, is a receptacle 17 including two compartments 18 and 19, this receptacle having in the present instance only one open face and access to its interior being prevented by means of a closure 20 which according to the present exemplification is slidably mounted within grooves 21 formed in the side walls of the receptacle. The closure 20 is connected by means of a link 22 with a lever 23 pivotally mounted upon the standard 10, and this lever has at its inner end a weight 24 tending normally to move this end of the lever downwardly and the closure upwardly to the position shown in Fig. 1. In order to guard against such movement the closure carries a notched bar or strip 25 against which a latch lever 26 in the form of a yoke may bear, to enter either one of the two notches in the manner shown in Figs. 2 or 3, thus preventing an upward movement of the closure. Secured to the standard is a further latch lever 27, the position of which, with respect to the lever, may be maintained by a link 28, the end of this latch member riding into a notch 30 formed in the upper edge of the lever 23 when the parts are in the position shown in Fig. 1, it being finally noted, with reference to this form of the invention, that the end of the lever 23 is formed with an extension 31 overlying the path of travel of the inner end of the lever 13 and acting as a stop for this member.

In operation it will be perceived that with access to the compartments of the receptacle barred by means of the closure as in Fig. 3, the semaphore arm may be operated in the usual manner to be thrown from clear to stop positions, or to the intermediate caution position. It is intended that the compartment 19 shall receive order blanks upon which there is to be inscribed orders of importance, but the compartment 18 receives order blanks of the first importance, these two sets of blanks being usually imprinted and/or colored so that they may be distinguished readily. As afore brought out, the first type of order does not require a stopping of the train unless the crew fails to "pick up" the order as the train, at comparatively reduced speed, passes the signal station. Orders within the compartment 18, however, are of that type which according to law and regulations require a complete stopping of the train and a receiving by the crew for the delivery of such order. If, now, an operator receives a message of the first type, he, in order to inscribe the same, will release the yoke 26 from engage-

ment with the upper notch of the strip or bar 25 and will raise the closure 20 to the position shown in Fig. 2 in order to gain access to the order blanks within the compartment 19 for the purpose of inscribing the order which has been received. Thereupon he may not carelessly manipulate the actuating member 14 in order to return the semaphore arm to the clear position. While this arm may be moved under this setting of the parts to the stop position, any attempt to move the same from the intermediate position to clear the right of way will be prevented by the fact that the lever 13 will strike against the stop 31 under such an attempt, and the semaphore arm accordingly can not reach the "clear" position. The operator, in order to clear the right of way, will have to primarily move the closure from the position of Fig. 2 to that of Fig. 3 and only thereupon may the lever 13 be moved to shift the semaphore arm to such position, it being obvious that such actuation of the parts may not be done through sheer absent-mindedness.

When an order of utmost importance is to be inscribed, the operator will move the closure 20 from the position of either Figs. 3 or 2 to the position of Fig. 1. In order to accomplish this, however, it is necessary, primarily to shift the lever 13 so that the lever 23 may be shifted. In so doing it is apparent that the semaphore arm is moved to the full stop position and a return from this position will be prevented, first, by the fact that the lever 13 will strike against the stop 31 under such attempt, and secondly, due to the fact that the lever 23 will be maintained against return movement, by the latch 27 having ridden into the notch 30. Consequently, if the semaphore arm is to be returned to the position of Fig. 3, an operator must primarily release this latch. Thereupon the closure must be moved downwardly and only then may the actuating member 14 be manipulated.

In Fig. 6 the invention has been shown as applied to that type of semaphore in which the signal arm is inclined downwardly instead of upwardly when a caution signal is being registered, and when this arm extends vertically downwardly from its pivot, to indicate a "clear track" condition instead of upwardly as in Figs. 1 to 3. Obviously as shown, the parts are similar to the structure afore described with the exception that the connecting member 32, instead of extending between the inner end of the lever 13 and the semaphore arm, extends from a point adjacent the outer end of the lever and may be provided by means of a flexible connecting element in lieu of the link 15.

In the form shown in Fig. 7 the semaphore arm is swung by a link 33 actuated by a bell-crank lever 34, this lever being swung by a rod 35 connected to one arm of a second bell-

crank lever 36, the opposite arm of which is connected by links 37 and 38, first to an actuating lever 39, and secondly with a block 40 having shouldered lower end 41 and being mounted for sliding movement upon a suitable support. In this form of signalling device it is obvious that as the actuating lever 39 is moved downwardly a pull will be imparted to the rod 35 resulting in the semaphore arm being swung upwardly to either intermediate or clear position. Pivotally mounted below the shoulders 41 is a stop 42 which may be rocked by means of a link 43, bell-crank lever 44, link 45, and lever 46 to occupy a position at which it intersects the path of travel of the shoulders 41. This position of the stop 42 is controlled by the position of the closure 20, which in turn may be shifted to open position only when the yoke 20 latch 26 is swung out of engagement with the notches of the strip or bar 25. A return of the closure to its initial position is prevented by means of a pawl 47 cooperating with a latch bar 48, the pawl having at this end two notches 49 either of which may be engaged by the bar according to position of the pawl, which in turn is dependent upon the position of the closure.

In this form of device it will be apparent that which the receptacle closed the actuating lever 39 may be shifted to swing the semaphore arm to any desired position. If, however, an operator desires access to orders of the first type afore referred to, he will, after swinging the yoke bar out of engagement with the notch associated with the closure, move the latter upwardly which will result (a) in the pawl 47 riding downwardly with respect to the bar 48 and having its lowermost notch interlocked therewith, it being obvious that this pawl serves in many respects to equalize the weight of the closure and its associated parts; (b) Such movement of the closure will cause the stop 42 to be disposed in line with the path of travel of the uppermost shoulder 41 under which conditions the semaphore arm may not be shifted beyond the caution position, although from this position it may still be freely shifted to the full stop position. If access to order blanks of major importance is to be had, the yoke latch may again be moved to permit the closure to move to the position shown in Fig. 7, which will cause the pawl 47 to ride downwardly to engage with its second notch, the bar 48, and furthermore cause the stop 42 to be swung to the position shown in this figure, in which position the semaphore arm may not be shifted. If the parts are to be released, this is capable of accomplishment only by first releasing the pawl 47 thereupon moving the closure downwardly and locking it against further movement, and only then may the semaphore arm be shifted.

Thus, among others, the objects specifically

forementioned are achieved, but it is intended that numerous changes in construction and rearrangements of parts may be resorted to without departing from the spirit of the invention, which are defined by the claims 70 as follows.

I claim:

1. A device of the character described including shiftable signalling means, a receptacle, means whereby the interior of said receptacle may be rendered inaccessible and means for limiting the shifting of said signalling means proportionate to the degree of accessibility of the receptacle interior. 75

2. A device of the character described including shiftable signalling means, a receptacle, means whereby the interior of said receptacle may be rendered inaccessible, means for limiting the shifting of said signalling means proportionate to the degree of accessibility of the receptacle interior, and means tending to prevent the interior of said receptacle again being rendered inaccessible. 80 85

3. A device of the character described including, in combination, a standard, a semaphore arm pivoted to the standard, a lever swingingly mounted upon said standard, means connecting said lever with said semaphore arm to shift the same, a receptacle having a plurality of compartments and a closure therefor, said semaphore having a plurality of positions, and a lever connected to move with said closure and providing a stop cooperating with the first named lever to prevent movement of the latter and the semaphore to a position beyond that determined by the position of the closure. 90 95 100

4. A device of the character described including a signal movable to one of a plurality of positions, a receptacle divided into compartments, a closure for said receptacle and movable to permit access successively to said compartments and means connecting said closure to said semaphore to limit the movement of the latter to a position corresponding 105 110 to the compartment to which access may be had.

5. A device of the character described including a movable semaphore arm, means for shifting the same to any one of several positions, a receptacle, a movable closure therefor, means connected with said closure to limit the movement of the semaphore arm when said receptacle is in open position, and means for preventing a closing of said receptacle. 115 120 125

6. A device of the character described including, in combination, a semaphore, means for shifting the same, a receptacle, a movable closure therefor, and means connected with said closure and cooperating with said semaphore shifting means to limit the movement of the latter when said receptacle is open.

7. A device of the character described including, in combination, a semaphore, means for shifting the same, a receptacle, a movable 130

closure therefor, means connected with said closure and cooperating with said semaphore shifting means to limit the movement of the latter when said receptacle is open, and means connected with said limiting means for normally preventing a closing of the receptacle.

8. A device of the character described including a receptacle, a movable closure therefor, means for normally retaining said closure against movement, a semaphore, means for freely shifting the same to various positions and means connected with said retaining means to limit such shifting when the receptacle is open.

13. 9. A device of the character described including a receptacle, a movable closure therefor, means for normally retaining said closure against movement, a semaphore, means for freely shifting the same to various positions and means connected with said retaining means to decrease the amount of movement of which said semaphore is capable in proportion to the opening of the receptacle.

10. A device of the character described including a semaphore arm, a lever connected therewith to shift the same to various positions, a receptacle, a notched bar, a closure secured to said bar and movable with respect to said receptacle, means cooperating with the notches of said bar to normally hold the latter and said closure immovable and means

connected with said bar and cooperating with said semaphore shifting means to limit the movement of the latter in proportion to the movement of said bar.

35

11. A device of the character described including a standard, a lever pivotally mounted thereon, a semaphore movable to various positions and connected with said lever to be operated thereby, a second lever pivoted to said standard, a movable receptacle closure connected with said second lever, said second lever extending adjacent said first lever and limiting the movement thereof proportionate to the position of the receptacle closure.

45

12. A device of the character described including a standard, a lever pivotally mounted thereon, a semaphore movable to various positions and connected with said lever to be operated thereby, a second lever pivoted to said standard, a movable receptacle closure connected with said second lever, said second lever extending adjacent said first lever and limiting the movement thereof proportionate to the position of the receptacle closure, and means cooperating with said second lever for preventing a movement of the closure to receptacle closing position after having been shifted to a position at which said receptacle is open.

55

In testimony whereof I affix my signature.

BEN ROBERT SMITH.
